UNITED STATES PATENT OFFICE

WILLIAM P. DAY AND FRANCIS M. CASE, OF CLEVELAND, OHIO, ASSIGNEES TO THE INTERNATIONAL STEEL TIE COMPANY, OF CLEVELAND, OHIO, A CORPORATION OF OHIO

PULSATING MACHINE FOR USE IN ROADBED CONSTRUCTIONS

Application filed January 30, 1930. Serial No. 424,589.

This invention relates generally to a pulsating or vibrating machine and more particularly to such a machine which is adapted for use in making roadbed construction for railways; and which is adapted to be supported by the rails of a railroad track and to impart vibrations to the track and ties, which vibrations are transmitted to the roadbed.

The main object of the invention is to provide a machine of the character described which is adapted for production at comparatively low cost and which is rigid and dependable in construction and in general well adapted for the purpose for which it is designed.

A further object of the invention is to provide a machine for imparting vibrations to a pair of rails of a railroad track and which is supported by and movable on the rails as desired.

A further object of the invention is to provide a machine of the character described which comprises essentially a frame, supported by and movable along the rails, and mechanism carried by the frame adapted for connection to the rails, together with means for imparting a vibratory motion to the rails and roadbed.

Further and more limited objects of the invention will appear as the description proceeds and by reference to the accompanying drawings in which Fig. 1 is a view in side elevation illustrating the preferred embodiment of our invention; Fig. 2 is a view in end elevation illustrating the vibrating machine mounted on a pair of rails of a railroad track; Fig. 3 is a fragmentary top plan view of the machine supported by the rails of a railroad track; Fig. 4 is a fragmentary vertical sectional view illustrating the driving connection with the motor for imparting the vibratory motion to the track; Fig. 5 is a vertical sectional view on the line 5—5 of Fig. 2; Fig. 6 is a fragmentary sectional view on the line 6—6 of Fig. 5; and Fig. 7 is a fragmentary sectional view on the line 7—7 of Fig. 5.

Referring now to the drawings, the reference character 1 designates the base or frame 50 of the machine which is preferably supported

on a pair of axles 2, only one of which is shown in the drawings. The axles 2 are supported by wheels 3 and 4 which are non-rotatably secured to the axles and are spaced apart such a distance as to engage the opposite rails of a track. The base or frame of the machine is substantially rectangular in shape and mounted on a suitable base 5 is an electric motor 5^a, although any other suitable type of motor may be employed. Extending 55 upwardly from the forward end of the frame at opposite sides thereof are a pair of parallel bars 6 and 6^a which lead upwardly therefrom at an angle as shown most clearly in Fig. 1. The bars 6 and 6^a are then bent rearwardly to provide horizontal portions 7 and 7^a and thence downwardly so as to provide rearwardly inclined portions 8 and 8^a. The ends of the bars 6 and 6^a are secured to the frame as shown in Fig. 1 in any suitable 60 manner, preferably by being welded thereto. Connecting the horizontal portions 7, 7^a of the bars 6 and 6^a is an angle iron 8^b. Carried by the angle iron 8^b and rotatably mounted thereon are a pair of pulleys 9 and 10 which are connected with each other by means of a shaft 11 journaled in suitable 65 bearings which are carried by angle iron 8^b, the purpose of which will hereinafter appear.

Extending upwardly from the base 1 are 70 a pair of parallel bars or frame members 12 and 13 which are bent rearwardly to provide horizontal portions 14 and downwardly extending portions 15 and 16. Connecting the horizontal portions 14 is an angle bar 16^a 75 which is secured thereto in any suitable manner, preferably by welding. Secured on the angle bar 16^a is a bearing 17 through which extends a shaft 18 to one end of which is non-rotatably secured a wheel 19. The opposite end of the shaft 18 is operatively connected with the shaft 11 through suitable 80 reducing gearing (not shown). By turning the wheel 19 the pulleys 9 and 10 may be turned in either direction. Secured to the 85 downwardly inclined portions 8 and 8^a of the bars 6 and 6^a are a pair of bearings 20 and 21 through which extends a shaft 22. Non-rotatably mounted on one end of the shaft 22 are pulleys 23 and 24 which are held 90

thereon by a collar 25. Non-rotatably mounted on the opposite end of the shaft 22 is a pulley 26. Secured to the downwardly inclined portions 15 and 16 of the bars 12 and 13 respectively are a pair of bearings 27 and 28. Secured within the bearing 28 is a shaft 29, on which is non-rotatably mounted a pulley 30. Non-rotatably secured on the outer end of the shaft 29 is a wheel 31. Connecting the pulleys 30 and 23 is a chain 32. Secured in the bearing 27 is a shaft 34 on which is non-rotatably secured a pulley 35. Non-rotatably secured on the outer end of the shaft 34 is a wheel 36 by means of which the shaft 10 may be turned. Non-rotatably secured on the shaft 2 is a pulley 37 which is operatively connected to the pulley 35 by means of a chain 38. By turning the wheel 36 the axle 2 will be turned and the vehicle moved along the 20 track.

The toggle mechanism for grasping the rails is suspended from the pulleys 9 and 10 by means of ropes 39 and 40 which extend around the pulleys respectively and are secured thereto. The toggle mechanism is mounted between a pair of somewhat triangular plates 41, 42 which are spaced apart and held together by blocks 43 and angle irons 44, 45 and 46 which are preferably welded 25 to the plates. The blocks 43 are spaced a slight distance from the ends of the plates so that the plates project slightly beyond the blocks, as shown in Fig. 5. Extending through the opposite ends of the plates 41 and 42 are a pair of pins 47, 48 on which are pivotally mounted pawls 49, 50. The lower ends of the pawls 49 and 50 are provided with notches 51 and 52 which are adapted to engage the rails, as shown most 30 clearly in Fig. 5.

Rigidly secured to and between the plates 41 and 42 are a pair of brackets 53 and 54. The brackets 53 and 54 are shown in detail in Figs. 6 and 7 and consist of a pair of plates 45 53^a and 53^b secured together by pins 55 and 56, 57 and 58. The ropes 39 and 40 extend around the pins 55 and 56 and flexibly support the plates 41 and 42 together with the mechanism carried thereby. Arranged within 50 the brackets 53 and 54 are a pair of cranks 59 and 60 which are shaped as shown most clearly in Figs. 2 and 5. The cranks 59 and 60 are pivotally mounted on the pins 57 and 58 as shown most clearly in Fig. 5. Pivotally connected with the cranks 59 and 60 are adjustable connecting links 61 and 62 which are connected with the cranks 59 and 60 by pins 63 and 64. The opposite ends of the links 61 and 62 are connected with 55 the pawls 49 and 50 respectively by pins 65 and 66. The upper ends of the cranks 59 and 60 are each provided with bores or passageways 67 and 68 in which are arranged threaded sleeves or bushings 69 and 70 60 through which a threaded shaft 71 extends.

Secured to the opposite ends of the shaft 71 are pulleys 72 and 73. For providing a driving connection between the shafts 22 and 71 we provide chains 74 and 75 which connect pulleys 24 and 72 and 26 and 73. It will therefore be seen that by rotating the wheel 31 the pawls 49 and 50 may be moved outwardly or inwardly as desired. Secured to the plates 41 and 42 is an upstanding bar or lever 76 which has a notch therein which 75 engages over the shaft 71 between collars 77 and 78 provided on the shaft 71, the purpose of which will hereinafter appear.

Carried by the plates 41 and 42 respectively are a pair of bearings 79 and 80 in which is journaled a shaft 81 on which is non-rotatably secured an eccentric 82. The shaft 81 is connected with the motor 5 by means of a flexible drive shaft 83. As the motor is driven, a rotary motion will be 85 given to the eccentric 82 which will impart a vibratory or pulsating motion to the plates 41 and 42 and the mechanism carried thereby as the plates 41 and 42 are suspended from the main frame by the flexible cables 39 and 40. These vibrations are transmitted to the rails through the medium of the toggle mechanism already described.

Carried by the shaft 22 adjacent the opposite ends thereof are two pairs of collars 84, 85 and 86, 87. Disposed between these pairs of collars respectively and engaging over the shaft 22 are a pair of bars or links 88 and 89. One end of each of the bars 88 and 89 is connected with the shaft 22 and the opposite ends of these bars are connected with brackets 90 mounted on the brackets 53 and 54, the purpose of which will hereinafter appear.

The operation of the device is as follows:—The vehicle is mounted on the track with the wheels resting on the rails and with the mechanism carried by the plates 41 and 42 supported above the rails. By turning the wheel 19, this mechanism is lowered until the blocks 43 engage the rails in the position shown in Fig. 5. By turning the wheel 31, shaft 71 will be turned through the medium of pulley 30, chain 32, pulley 23, shaft 22, pulleys 24 and 26, chains 74 and 75 and pulleys 72 and 73. As the shaft 71 has threaded engagement with the sleeves 69 and 70 which are carried by the upper ends of the cranks 59 and 60, the cranks 59 and 60 will be moved to the position shown in Fig. 5 and will engage the outer edges of the rails and firmly secure the mechanism to the rails. The motor 5 may then be started which will impart a rotary motion to the eccentric 82, which in turn will impart a vibratory or pulsating motion to the plates 41 and 42 and the mechanism carried thereby. It will thus be seen that a very violent motion will be imparted to the rails and as the rails are mounted on ties, this vibratory motion will 125 130 135 140 145 150 155 160 165 170 175 180 185 190 be imparted to the whole roadbed. When it is desired to move the vehicle forward or backward, the wheel 36 may be turned so as to turn the axle 2 on which the wheels 3 and 4 are non-rotatably mounted. When it is desired to move the vehicle, however, it is first necessary to turn the wheel 31 so as to move the pawls 49 and 50 out of engagement with the rails. The vehicle can then be moved either forward or backward as desired. The arms 88 and 89 serve to hold the plates 41 and 42 in the position shown in Figs. 1, 2 and 3 so that there will be no slack in the chains 74 and 75. These arms, together with bar 76 which is disposed between the collars 77 and 78, prevent the plates 41 and 42 from swinging either longitudinally or laterally when the pawls are disengaged from the rails.

20 Various changes may be made in the details of construction and arrangement of parts without departing from the spirit of our invention and it is understood that the embodiment of the invention herein disclosed is merely illustrative and not to be considered in a limiting sense. Our invention is therefore limited only in accordance with the scope of the appended claims.

Having thus described our invention, 30 what we claim is:

1. A machine for imparting vibrations to a railroad track and comprising a frame, wheels journaled on said frame and adapted to engage said track, vibrating mechanism 35 and means for imparting the vibrations to the track.

2. A machine for imparting vibrations to a pair of rails of a railroad track comprising a supporting member adapted to be moved 40 along the track, vibrating means carried by said supporting member and means for transmitting said vibrations to said rails.

3. A machine for imparting vibrations to a pair of rails of a railroad construction comprising a support movably mounted on said rails and having a depending portion adapted 45 for engagement with said rails, and means for imparting vibrations to said rails.

50 4. A machine for imparting a vibratory motion to the rails of a railroad roadbed construction and comprising a frame supported by and movable along the rails, mechanism carried by said frame and adapted 55 for connection with said rails and power means for imparting a vibratory motion to said rails.

5. A machine for imparting a vibratory motion to the rails of a railroad roadbed construction and comprising a frame supported by and movable along the rails, mechanism carried by said frame and adapted for connection with said rails and power means for imparting a vibratory motion to said rails, said mechanism including rail gripping de-

vices adapted to be adjustably connected with said rails.

6. A machine for imparting a vibratory motion to the rails of a railroad roadbed construction and comprising a frame supported by and movable along the rails, mechanism carried by said frame and adapted for connection with said rails, power means for imparting a vibratory motion to said rails, said mechanism including a plurality of rail gripping devices movable with respect to said rails, and means for moving said machine along the rails.

7. A machine for imparting a vibratory motion to the rails of a railroad roadbed construction and comprising a frame supported by and movable along the rails, mechanism carried by said frame and adapted for connection with said rails, power means for imparting a vibratory motion to said rails, said mechanism including a plurality of rail gripping members adapted to be connected to said rails, means for moving said machine along the rails, said power means comprising a motor and a flexible driving connection between said motor and mechanism.

8. A machine for imparting a vibratory motion to the rails of a railroad roadbed construction and comprising a truck, a frame adjustably mounted with respect to said truck, mechanism carried by said frame and adapted for connection with said rails, power means for imparting a vibratory motion to said rails, said mechanism including a plurality of members adjustably connected with said frame and adapted to engage said rails, means for moving said machine along the rails, said power means comprising a motor, a flexible driving connection between said motor and frame, and flexible connections between said truck and frame.

9. In a machine for imparting a vibratory motion to the rails of a railroad roadbed construction, the combination of a frame, wheels journaled on said frame and adapted to engage said rails, rail gripping devices suspended from said frame, a motor carried by said frame and having a shaft, an eccentrically mounted member for operating said rail gripping devices, a driving connection between said member and motor shaft, said rail gripping devices including means for rigidly connecting the same with said rails.

10. In a machine for imparting a vibratory motion to the rails of a railroad roadbed construction, the combination of a frame, wheels journaled on said frame and adapted to engage said rails, a rail gripping device suspended from said frame, a motor carried by said frame and having a shaft, an eccentrically mounted member journaled in said rail gripping device, a driving connection between said member and motor shaft, said rail gripping device embodying means for rigidly connecting the same with said rails, the con-

nection between said rail gripping device and frame including means for preventing excessive vibration of said frame.

11. In a machine for imparting a vibratory motion to the rails of a railroad roadbed construction, the combination of a truck frame, wheels journaled on said frame and adapted to engage said rails, a rail gripping device suspended from said frame, a motor carried by said frame and having a shaft, an eccentrically mounted member journaled in said rail gripping device, a driving connection between said member and motor shaft, said rail gripping device embodying means for rigidly connecting the same with said rails, the connection between said rail gripping device and frame including means for preventing excessive vibration of said frame, the driving connection between said motor shaft and eccentrically mounted member being flexible.

12. A machine for imparting a vibratory motion to a railroad track of a roadbed construction comprising a frame, means movably supporting said frame on the track, a motor carried by said frame, mechanism carried by said frame and adapted to be detachably secured to the track, and a driving connection between said motor and mechanism including means for imparting a vibratory motion to the track.

13. A machine for imparting a vibratory motion to a railroad track of a roadbed construction comprising a frame, means movably supporting said frame on the track, a motor carried by said frame, mechanism carried by said frame and adapted to be detachably secured to the track, a driving connection between said motor and mechanism including means for imparting a vibratory motion to the track, and means carried by said frame for moving said mechanism into or out of engagement with the track.

14. A machine for imparting a vibratory motion to a railroad track of a roadbed construction comprising a frame, means movably supporting said frame on the track, a motor carried by said frame, mechanism carried by said frame and adapted to be detachably secured to the track, a driving connection between said motor and mechanism including means for imparting a vibratory motion to the track, means carried by said frame for moving said mechanism into or out of engagement with the track, and means for moving said machine along the track.

15. A machine for imparting a vibratory motion to a railroad track of a roadbed construction comprising a frame, means movably supporting said frame on the track, a motor carried by said frame, mechanism carried by said frame and adapted to be detachably secured to the track, a driving connection between said motor and mechanism including means for imparting a vibratory motion to the track, means carried by said frame for

moving said mechanism into or out of engagement with the track, means for moving said machine along the track, flexible means supporting said mechanism from said frame, and a flexible driving connection between said mechanism and motor.

16. A machine for imparting vibratory motion to the rails of a railroad roadbed construction and comprising a frame adapted to be movably supported on the track, a motor carried by said frame, mechanism suspended from said frame and having a pair of gripping devices pivotally mounted thereon and adapted for engagement with the rails, an eccentrically mounted member journaled in said mechanism, a flexible driving connection between said eccentrically mounted member and motor, means for moving said gripping devices into and out of engagement with said rails, means for raising and lowering said mechanism as a whole, the connection between said mechanism and frame being flexible whereby the vibrations of said mechanism will not be freely transmitted to the frame.

17. A machine for imparting vibratory motion to the rails of a railroad roadbed construction comprising a frame adapted to be movably mounted on the track, a motor carried by said frame, a rail gripping device suspended from said frame by means of a flexible connection, a shaft journaled on said frame, means for turning said shaft to raise and lower said rail gripping device, said rail gripping device including a pair of arms adapted to detachably engage said rails, a second shaft journaled on said frame, and operable connections between said second shaft and said pair of arms, means for turning said second shaft to move said arms into and out of engagement with said rails and a flexible driving connection between said motor and rail gripping device including means for imparting a vibratory motion thereto.

18. A machine for imparting vibration to a railroad track comprising a frame adapted to be moved along the rails, a power operated vibrating mechanism carried by said frame and adapted to impart vibrations to the track and means for connecting said vibrating mechanism with the rails.

In testimony whereof, we hereunto affix our signatures.

WILLIAM P. DAY.
FRANCIS M. CASE.
